UNITED STATES PATENT OFFICE.

CHARLES E. BERRY, OF SOMERVILLE, MASSACHUSETTS.

HYDRANT-WRENCH.

1,114,723.

Specification of Letters Patent.

Patented Oct. 27, 1914.

Application filed May 25, 1914. Serial No. 840,877.

To all whom it may concern:

Be it known that I, CHARLES E. BERRY, a citizen of the United States, residing at Somerville, in the county of Middlesex and 5 State of Massachusetts, have invented a new and useful Hydrant-Wrench, of which the following is a specification.

This invention relates to a hydrant wrench, one of its objects being to provide 10 a simple and compact device of this character for use in connection with screw heads of different sizes whereby the wrench can be used in connection with different makes of hydrants.

15 A further object is to provide a simple form of spanner in connection with the wrench by means of which hose can be attached readily to a hydrant, thus rendering the tool especially desirable for use by fire 20 departments.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without 30 departing from the spirit of the invention.

In the accompanying drawings the preferred form of the invention has been shown.

In said drawings:—Figure 1 is a side elevation of a wrench embodying the present 35 improvements. Fig. 2 is a front elevation thereof. Fig. 3 is an end elevation. Fig. 4 is a section on line A—B Fig. 2.

Referring to the figures by characters of 40 reference, 1 designates an elongated handle or shank merging, at one end, into a ring 2 from which extends outwardly diverging arms 3 connected by an arcuate web 4, these arms 3 being formed with longitudinal slots 45 5 while the web 4 is also slotted longitudinally, as shown at 6. The arms 3 and the web 4 constitute a spanner whereby hose can be connected to a hydrant in the usual manner, as will be obvious. The spanner and 50 the shank 1 are disposed at diametrically opposed points on the ring 2. The inner surface of the ring is formed with diametrically opposed flattened faces 7 equidistant from the handle 1 and extending through 55 each flattened face is a pivot screw 8, the in-

ner end of which constitutes the bearing trunnion as shown at 9.

A ball 10 is arranged loosely within the ring 2 and has opposed flattened faces 11 each of which is formed with a socket 12 60 designed to receive the bearing portion 9 of one of the screws 8. The ball is balanced upon these trunnions and is adapted to rotate readily within the ring 2. Formed within the ball are radially disposed pentagonal sockets 13 of different sizes. Preferably four of these sockets are employed, the ball being formed with flattened faces 14 where these sockets are located. A reinforcing bar 15 is formed integral with the 65 ball and extends diametrically therethrough in alignment with the pivot or bearing 9.

Extending from one face of the shank or handle 1 is a boss 16 having a pentagonal socket 17 in its outer end and, formed in 70 the inner end of this pentagonal socket is a smaller rectangular socket 18, as shown in Fig. 2.

In using the wrench, the ball 10 is rotated until a socket 13, which will fit the screw 80 head to be rotated, is brought into position to engage said screw head. As the screw heads of various makes of hydrants vary in size, it will be seen that by utilizing a ball 10 having sockets of different sizes, the 85 same can be fitted readily to screw heads of different sizes. Moreover, as all of the sockets are located in a ball mounted for rotation, it will be seen that the handle will always occupy the same relation to any one 90 of the sockets 13 into which the screw head of the hydrant may extend.

Many hydrants are provided with small outlets controlled by a valve, the stem or actuating screw of which has a comparatively small head. These heads are somewhat rectangular and some times pentagonal. For the purpose of engaging and rotating these small heads, the boss 16 has been provided, socket 17 being used for receiving a pentagonal head, while socket 18 is provided for receiving a rectangular head.

The bar 15 not only serves to reinforce the ball 10 but also constitutes a stop for limiting the movement of the engaged head 100 of a screw into the ball.

What is claimed is:—

A wrench including a ring, a handle extending therefrom, said ring having its wall thickened at diametrically opposed points, 110

bearing elements screwed into said thickened portion and projecting into the ring, and a ball mounted for rotation on the projecting ends of said elements and having a plurality of radial sockets, there being a reinforcing bar within the ball and alining with the bearing elements, said bar constituting a stop.

In testimony that I claim the foregoing as my own, I have hereto affixed my signature in the presence of two witnesses.

CHARLES E. BERRY.
